BLOCK MODULE FOR BUILDING STATUES, ART PIECES OR THE LIKE

Stanley Tigerman, Chicago, Ill., assignor to Stanley
Tigerman, Ltd., Chicago, Ill.

Filed Nov. 24, 1969, Ser. No. 20,234

Term of patent 14 years

Int. Cl. D25—01

U.S. Cl. D18—2

*Fig. 5.**Fig. 6.**Fig. 7.**Fig. 8.*FIG. 1 is a top perspective view of a block module for building statues, art pieces or the like showing my new design;

FIG. 2 is a bottom perspective view of the block module for building statues, art pieces or the like of FIG. 1;

FIG. 3 is a top plan view of the block module for building statues, art pieces or the like of FIG. 1;

FIG. 4 is a bottom plan view of the block module for building statues, art pieces or the like of FIG. 1;

FIG. 5 is an elevational view of either side of the block module for building statues, art pieces or the like of FIG. 1;

FIG. 6 is an elevational view of either end of the block module for building statues, art pieces or the like of FIG. 1;

FIG. 7 is a longitudinal sectional view of the block module for building statues, art pieces or the like of FIG. 1 taken along section line 7—7; and

FIG. 8 is a transverse sectional view of the block module for building statues, art pieces or the like of FIG. 1 taken along section line 8—8.

I claim:

The ornamental design for a block module for building statues, art pieces or the like, substantially as shown.
